HUDSON, NEW YORK, A CORPORATION OF NEW YORK

LOWERING MACHINE

Application filed January 14, 1929. Serial No. 332,459.

This invention relates to improvements in elevators and, among other objects, aims to provide an improved elevator installation and means to prevent the elevator from falling should the supporting cable break.

In the drawings,

Fig. 1 is a side elevation of one embodiment of the invention;

Fig. 2 is a side elevation on an enlarged scale of a portion of the elevator showing one of the safety devices;

Fig. 3 is an end elevation of the same;

Fig. 4 is a vertical sectional view also on an enlarged scale taken through the cable gripping mechanism at the top of the elevator car;

Fig. 5 is a vertical sectional view taken at right angles to Fig. 4; and

Fig. 6 is a horizontal sectional view taken on the line 6—6 of Fig. 3.

Referring particularly to the drawings, the improved mechanism is shown as being applied to an elevator of the type generally used in ice plants, which consists essentially of a counterweighted platform or gig 10 supported at both ends and mounted to slide vertically on timber-covered standards or guides 11. These elevators are normally used for lowering ice or the like from one level to a lower level, the counterweights being so adjusted that they are heavier than the empty gig, thus causing the gig to ascend, and lighter than the loaded gig, which will descend of its own weight.

The gig is usually held in both the top and bottom positions by manually operated catches (not shown) which, of course, must be released before the loaded gig descends or the empty gig ascends, as the case may be.

To prevent a too rapid descent or ascent, the counterweights move up and down in cylinders which are filled with a liquid, thus checking travel of the counterweights, but as this feature forms no part of the present invention, it has not been shown.

In such elevator installations, the gig is usually supported by a rope or cable at each end and one or both of the cables, in time, are liable to break, so that the gig drops with its load. Except on very rare occasions, only

one rope breaks, thus causing the gig to fall in a canted position and spill its load or fall to the lower level, so that the gig is damaged by being sprung out of shape.

The present invention obviates these undesirable results by a novel cable arrangement combined with means which will catch and hold the gig on an even keel at any point of its travel, should the supporting cable break. To this end, only one rope or cable 12 is employed, the same being secured at its ends to counterweights 13 at opposite ends of the elevator and passing over guide sheaves 14 at the top of the supporting structure and under slidably mounted sheaves 15 at each end of the gig, the sheaves 15 being operatively connected to safety devices (about to be described) in such a manner that the safety devices are held in inoperative or normal position so long as the cable remains intact and taut.

Each of the safety devices, of which there is one at each end of the gig, comprises a pair of gripping dogs 16 (Fig. 3), eccentrically mounted for oscillation on horizontal shafts 17 carried by supporting brackets 18 secured to the end wall 19 of the gig and to the upper framework 20. The dogs of each pair are arranged opposite to each other and on opposite sides of and in vertical alignment with strips of wood 21 secured to the adjacent guide 11 (Figs. 2, 3 and 6). The dogs are each formed with transverse teeth on the curved side adjacent to the strip 21 and are so arranged that when they are rocked, their teeth will bite into the wooden strips and support the gig.

The mechanism for actuating each set of dogs is shown in Figs. 2 and 3 as comprising a vertically disposed plunger 22 slidably mounted in a guide member 23 secured on the outside of the end wall 19. The upper end of the plunger 22, which extends above the guide member 23, is bifurcated as shown in Figs. 3 and 6, so that one of the sheaves 15 may be rotatably mounted between the side arms on a suitable shaft or axle. The plunger extends below the guide member 23 and carries a crosshead 24 at its lower end. This end of the plunger is preferably screw-

- threaded and has an adjusting nut 25 thereon, so that the crosshead, which is slidable on the plunger above the nut, may be adjusted vertically on the plunger. A crank 26 (Fig. 3) is secured to or formed integrally with each dog and extends outwardly therefrom and is pivotally connected to the upper end of a link 27, whose lower end is pivotally connected to one side of the crosshead.
- 6 10 An expansile coil spring 28 is shown surrounding the plunger between the crosshead and the lower end of the guide member, normally urging the dogs toward their gripping positions.
- 15 To support the gig by the cable 12, the guide members 23 are preferably shaped like an inverted U, to provide a supporting bail 29, and the sheave 15 (which normally does not rotate), is adapted to abut against the 20 lower side of the bail, so that the gig is supported directly on the two sheaves 15 which in turn are supported by the cable passing beneath them, as before described. The sheave pin extends through vertical slots in 25 the sides of the bail. This arrangement relieves the plunger and all of the moving parts of all strain.

The weight of the gig (whether loaded or empty) keeps the cable taut and holds both 30 plungers 22 in their uppermost or normal position, as shown in Fig. 3, with the dogs out of engagement with the wooden strips and with the springs 28 compressed. Should the tension on the cable be released, as by 35 breaking, the springs 28 would expand and force the crossheads downwardly, thereby rocking the dogs inwardly against the strips by means of the link connections, so that the teeth bite into the strips and thus prevent the 40 gig from falling. By using but a single cable, it is apparent that should it break at any point, the tension would be released throughout the entire length and both of the gripping devices would operate instantly and 45 simultaneously to support both ends of the gig on an even keel.

As but one rope is used, it is evident that should the gig be loaded unevenly, or should the friction on the guides be unequal, a certain amount of slip and creeping of the cable would occur, permitting the gig to cant so that one end would be higher than the other, or one counterweight higher than the other, causing one weight to strike the bottom or top 55 of the cylinder in which it is mounted before the gig had completed its travel.

To prevent the canting, a device is provided to grip the cable at its approximate mid length, so that the cable in effect becomes 60 two cables, each secured at one end to a counterweight and at the other end to one end of the gig. The device is constructed so that should the cable break, the grip would be released.

65 The gripping device is herein shown as

comprising a cluster of three sheaves 30, 31 and 32 (Figs. 1, 4 and 5) arranged on the top of the upper framework 20. The two sheaves 30 and 32 are mounted in both horizontal and vertical alignment in a stationary 70 bracket 33, the distance between their adjacent edges being less than the diameter of the third sheave 31, which is located above and in vertical alignment with them on a vertically slidable support 34. The cable passes 75 beneath the two side sheaves 30 and 32 and over the central sheave 31, so that the tension in the cable draws the sheave 31 down, compressing an expansile coil spring 35 which surrounds the support between the framework and an abutment 36 on the support. 80

The grooves in all of the sheaves are of less depth than half the diameter of the cable so that the cable is normally gripped between the sheaves 30 and 32 and the sheave 31, when the latter is drawn downwardly. In case the cable breaks at any point, its tension will be lost and the spring 35 will force the central sheave 31 upwardly thereby releasing the grip on the cable and permitting both sets of 90 dogs to operate.

From the foregoing description it will be apparent that the improved gripping devices and cable sheaves may easily be applied to an old elevator so that it can be operated by a 95 single cable. Moreover, the attachment can be manufactured at a very low cost. Further, the mechanism is arranged positively to prevent the elevator from falling or canting as soon as the single cable becomes slack from 100 whatever cause.

Obviously, the present invention is not restricted to the particular embodiment thereof herein shown and described. Moreover, it is not indispensable that all the features of the invention be used conjointly, since they may be employed advantageously in various combinations and sub-combinations. 105

What I claim is:—

1. An elevator installation comprising, in combination, a pair of vertical guides; an elevator slidably mounted on said guides; a sheave at the top of each guide; a slidably mounted sheave at each end of the elevator; a cable having lifting weights secured to its ends, said cable passing over the two sheaves at the top of the guides and beneath the slideable sheaves with its mid portion between said slideable sheaves; means connected to the slideable sheaves to engage the guides and prevent the elevator from falling when the cable breaks; and means on the elevator to grip the cable intermediate its ends when the cable is taut and to release the grip when the cable breaks. 110

2. An elevator installation comprising, in combination, a pair of vertical guides; an elevator slidably mounted on said guides; a sheave at the top of each guide; a slidably mounted sheave at each end of the elevator; 115

a cable having lifting weights secured to its ends, said cable passing over the two sheaves at the top of the guides and beneath the slideable sheaves with its mid portion between said slideable sheaves; a pair of dogs at each end of the elevator arranged to engage the guides when released; and means operably connected to each pair of dogs and to the adjacent slideable sheave to release said dogs when the cable breaks.

10 3. An elevator installation comprising, in combination, a pair of vertical guides; an elevator slidably mounted on the guides; a sheave at each end of the elevator; a lifting cable for the elevator; said cable extending across the elevator from end to end and beneath both sheaves; and means intermediate 15 the sheaves at the ends of the elevator for clamping the cable, said means automatically 20 releasing the cable when the cable breaks.

4. An elevator installation comprising, in combination, a pair of vertical guides; an elevator slidably mounted on the guides; a slideably mounted sheave at each end of the elevator; a lifting cable for the elevator; said cable extending across the elevator from end to end and beneath both sheaves; means operably connected to each sheave to engage the guides and prevent the elevator from falling 25 when the cable breaks; and means on the elevator to grip the cable between the sheaves and prevent its movement relative to the sheaves when the cable is taut and to release the grip when the cable breaks.

30 5. An elevator installation comprising, in combination, a pair of vertical guides; an elevator slidably mounted on the guides; a slideably mounted sheave at each end of the elevator; a lifting cable for the elevator; said cable extending across the elevator from end to end and beneath both sheaves; a pair of gripping dogs rockably mounted at each end of the elevator, the dogs in each pair being on opposite sides of a guide to engage said guide 35 when released; and means operably connected to each of the sheaves and to the adjacent pair of dogs to release the dogs when the cable breaks and permit the dogs to engage the guides.

50 6. In an elevator of the class described, a substantially rectangular load platform; vertical guides at the opposite ends of the platform; cable sheaves supported on the guides at the upper ends; a cable sheave at each end 55 of the platform adjacent to vertical guides; a vertical plunger supporting each sheave; a pair of pivoted gripping dogs on opposite sides of each guide; links connecting the lower ends of the plungers with the dogs; a 60 spring associated with each plunger arranged to operate the gripping dogs; and a single lifting cable trained over the sheaves on the guides and under the sheaves on the platform normally to hold the gripping dogs 65 inactive when the cable is taut, said spring

plungers being adapted to actuate the gripping dogs simultaneously at both ends of the platform when the cable breaks.

7. An elevator installation comprising, in combination, a pair of vertical guides, an elevator slidably mounted on said guides; a slideably mounted sheave at each end of the elevator; an elevator-supporting cable passing beneath the slideable sheaves; a pair of arcuate dogs eccentrically pivoted to the elevator at each end thereof and on each side of the guides, said dogs having transverse teeth for engagement with said guides; and mechanism connecting the slideable sheaves with said dogs so that the dogs automatically engage the guides and prevent the elevator from falling when the cable breaks.

In testimony, that I claim the foregoing as my own, I have hereto affixed my signature.

OTTO BIRMANN.
